UNITED STATES PATENT OFFICE.

NORBERT SCHREIBER AND RAPHAEL ROSENTHAL, OF LINCOLN, ILLINOIS.

BOILER-SKIMMER.

1,187,182.

Specification of Letters Patent. Patented June 13, 1916.

Application filed March 4, 1915. Serial No. 12,013.

To all whom it may concern:

Be it known that we, NORBERT SCHREIBER and RAPHAEL ROSENTHAL, citizens of the United States, residing at Lincoln, in the 5 county of Logan and State of Illinois, have invented a certain new and useful Improvement in Boiler-Skimmers, of which the following is a full, clear, concise, and exact description, reference being had to the accompanying drawings, forming a part of this 10 specification.

Our invention relates to boiler skimmers or like devices, and especially to a type or construction of boiler skimmer adapted for 15 use in locomotive boilers.

Prominent objects of the invention are to provide a simple and practical boiler skimmer arrangement by which a locomotive boiler may be effectively skimmed, and especially to permit this to be done by a continuous 20 discharge or blow-off, to arrange for the control of this continuous discharge or blow-off, to make the same greater or less as desired; to permit the unrestrained or full discharge 25 whenever desired; to arrange to protect the apparatus from injury or meddling, and also to protect it from the weather and otherwise; to arrange for convenient access to the parts to be operated; and to secure the foregoing 30 and other desirable results in a simple and expeditious manner.

In the accompanying drawings Figure 1 is an elevation partly in section of a portion of a locomotive boiler provided with a skimming apparatus embodying our present invention; Fig. 2 is a plan view of the skimming device proper; and Figs. 3 and 4 are views of details of construction.

The arrangement shown in Fig. 1 comprises 40 a locomotive boiler 1, which may be of any usual type, a steam dome 2 being also shown. Within the boiler we show the usual dry pipe 3. We also show a throttle lever 4 arranged at the rear of the boiler and connected with a rod 5 which is understood to be operated by said lever 4 in the usual way to open and close the throttle valve (not shown). We show also a skimming device 6 which may be of various forms or constructions, a preferred form being shown in Fig.

2. In such arrangement side pipes 7—7 are provided, the same having apertures 8—8 forming surface intakes. An end pipe 9 is provided, the same being elevated with reference to the lower pipe 7 and connected with 55 the same by vertical pipes 10. Side or supplemental pipes or members 11 are provided extending lengthwise of the pipe 7 and floats 12 are shown mounted upon the supplemental pipes 11. The elevated pipe 9 fits above 60 the dry pipe 3. A discharge pipe 14 extends rearwardly from the skimmer 7, being connected with the same by a swivel joint 15, and also with a swivel joint 16. The end of the skimmer 7 adjacent the several connections 15 and 16 is supported upon a rod 17 extending to the dry pipe 3. A connection is shown between the throttle valve rod 5 and the skimmer by which the latter may be discharged or blown off by the operation of 70 the throttle valve lever 4. The particular form of connection shown comprises a finger or pin 18 extending downwardly from the valve rod 5 and arranged to work in a slot 19 formed in a lever 20 (Fig. 4) connected 75 with a valve 21 in an extension 22 of the discharge pipe 14. In this way the throttle lever 4 when operated to open the throttle valve will also operate the valve lever 19 so as to open the valve 21 and thereby permit 80 the discharge or blow off of the skimmer 7, and this blow-off or discharge will be continuous during the time the throttle valve is open. When, however, the throttle lever 4 is operated to close the engine throttle valve, 85 the lever 20 will also be operated so as to close the valve 21 and thereby shut off the discharge or blow-off from the skimmer.

It will be noticed that all of the parts excepting the throttle lever 4 and the extreme 90 end of the rod 5 connected therewith are located inside of the locomotive boiler, whereby they are protected and prevented from freezing in cold weather. A pipe 23 is connected with the valve 21 and this pipe extends to the wall of the boiler and through the same at 24 and is then connected with an outside drain or discharge pipe 25. This latter pipe may extend to various different 95 positions suitable for the discharge of the 100

matter passing through the skimmer, a preferred arrangement being to locate the end of said pipe so that the discharge will be upon the track on which the engine travels in front of or in the vicinity of one or more of the driving wheels. The pipe 25 is preferably provided with a plug valve 26 shown in detail in Fig. 3. This plug valve has an orifice or bore 27 which is controlled by an adjustable screw 28 so as to more or less restrict the flow of the discharge passing through the member 26. There is also shown a supplemental discharge pipe 29 which also preferably extends down into the neighborhood of the end of the pipe 26. This pipe 29 is provided with a globe valve 30 having a handle 31 which can be operated manually. Thus the pipe 29 may be opened wide whenever desired by operating the wheel 31 to permit a free and unrestricted blow-off of the skimming device. These pipes 25 and 29 and the valves 26 and 30 are preferably outside of the boiler so as to permit ready access to the same for adjusting the valves 26 and 30.

It will be understood that changes and modifications may be made without departing from the spirit of the invention.

In an application filed by us October 17, 1914, Serial No. 867,055, boiler skimmers, we disclose an apparatus containing certain of the features of construction and operation herein set forth and claim certain of said features in said other application.

35 What we claim is:

1. The combination with a locomotive boiler and throttle valve, of a skimming device located within the boiler, a valve controlling the skimming device, tubular connections between the valve and the skimming device, a member supporting the controlling valve and the skimming device, and connected with the tubular connections between the valve and the skimming device, said skimming device being hingedly connected to the tubular connections between it and the controlling valve.

2. The combination with a locomotive boiler and throttle valve arrangement therefor, of a skimming device located within the boiler and a connection between said throttle valve arrangement and the skimming device also located within the boiler, and a pair of discharge pipes for said skimming device located outside of the boiler.

60 3. The combination with a locomotive boiler and throttle valve arrangement therefor, of a skimming device located within the boiler and a connection between said throttle valve arrangement and the skimming device also located within the boiler, and discharge pipes for said skimming device located outside of the boiler, one of said discharge pipes

being provided with a restricted orifice and means for varying the size of the same. 65

4. The combination with a locomotive boiler and throttle valve arrangement therefor, of a skimming device located within the boiler and a connection between said throttle valve arrangement and a skimming device 70 also located within the boiler, and discharge pipes for said skimming device located outside of the boiler, one of said discharge pipes being provided with a restricted orifice and means for varying the size of the same, and 75 another of said discharge pipes being provided with a manually controlled valve.

5. The combination with a locomotive boiler and throttle valve arrangement therefor, of a skimming device located within 80 the boiler, a connection between said skimming device and said throttle valve arrangement, and a discharge pipe having a restricted orifice and an adjusting screw for adjusting the size of said orifice. 85

6. The combination with a locomotive boiler and throttle valve arrangement therefor, of a skimming device located within the boiler, a connection between said skimming device and throttle valve arrangement 90 whereby the discharge of the skimming device may be controlled by the throttle valve lever, and two discharge pipes for said skimming device, one of the same being provided with a restricted orifice and means for varying 95 the restriction thereof, and the other being provided with a manually operable valve, to permit free and unrestricted discharge.

7. The combination with a locomotive 100 boiler and throttle valve, of a skimming device located within the boiler, a valve controlling the skimming device, connections between the throttle valve, skimming device and controlling valve, all of which are 105 located wholly within the boiler, a support for said skimming device and the controlling valve, said support being connected to a member provided within the boiler.

8. The combination with a locomotive 110 boiler and throttle lever thereof, of a skimming device located within the boiler and having an outlet valve at its end, a mechanical connection between said outlet valve and said lever whereby said valve is opened and 115 closed when the throttle valve is opened and closed, an outlet pipe for said skimming device extending to and through a side wall of the boiler, and a pair of discharge pipes one of which is a blow-off pipe extending 120 downwardly from the end of said outlet pipe which is outside of said boiler.

9. The combination with a locomotive boiler and throttle valve, of a skimming device located within the boiler, a valve controlling the skimming device, a rod con- 125

nected to the throttle valve, a lever connected to an end of said rod, a member provided upon the rod between the throttle valve and the lever, said member being connected to the controlling valve, said last mentioned member and the controlling valve being located wholly within the boiler.

5 In witness whereof, we hereunto sub-

scribe our names this 11th day of February, A. D. 1915.

NORBERT SCHREIBER.
RAPHAEL ROSENTHAL.
